LOW AMPLITUDE AUDIO FREQUENCY
SWITCHING SYSTEM

William J. Morlock, Indianapolis, Ind., assignor to
Radio Corporation of America, a corporation
of Delaware

Application April 29, 1941, Serial No. 390,930

7 Claims. (Cl. 179—1)

This invention relates to low amplitude audio frequency switching systems. More particularly, the invention relates to a relay system for transferring or switching low amplitude or low level audio frequency signal conveying circuits by remote control.

Low level audio frequency circuits, as referred to herein, may include a plurality of microphone or photocell signal pickup circuits and the like, which operate at extremely low audio frequency level and which convey no appreciable current or voltage.

As such circuits operate at extremely low audio frequency signal levels, they are normally connected to high gain amplifying means for converting the signal from a source into a signal of useful magnitude. Accordingly, such low level circuits are sensitive to hum and noise signal pickup, and transfer or switching means employed therein must provide low resistance and stabilized connections involving low and constant contact resistance under all conditions of operation, even when the switching or transfer means is subjected to extreme vibration.

Because of the universal availability of the supply, it is desirable, and is present practice, to operate relays and other remote control switching means with alternating current. However, when used to energize the relay coils for transferring or switching low amplitude level audio frequency circuits, such as microphone and photocell pickup circuits, considerable difficulty has been encountered heretofore because of (1) pickup of alternating current voltages from the relay coil circuit, (2) pickup of stray voltages from the supply leads to the relay operating windings or coils in close proximity to the audio frequency conveying leads connected with the relay contacts, (3) lack of sufficient sliding or wiping contact in the switching means to prevent an appreciable or variable contact resistance and with no contact voltage sufficient to break down the contact resistance, and (4) contact vibration when subjected to shock or vibration, as in gun-fire control systems and the like, or in rapidly moving vehicles.

It is, therefore, a primary object of this invention to provide an improved low amplitude level, audio frequency transfer or switching system adapted for remote operation, which substantially prevents contact vibration and stray voltage pickup from the operating circuits. It is also an object of the invention to provide an improved relay or switching device which is simple and dependable in construction and operation over

long periods of time and under adverse operating conditions including extreme vibration.

It is a further object of this invention to provide a low level audio frequency relay or circuit switching means which is adapted for alternating current operation and the switching control of low amplitude level audio frequency circuits, without complicated wiring connections thereto, while substantially eliminating stray hum voltage pickup.

It is a still further object of this invention to provide an improved relay or circuit switching means for low amplitude level audio frequency circuits which is adapted for multiple operation in groups, while electrically isolating or shielding the operating and controlled circuits whereby alternating current may be used for energizing the switching means.

In accordance with the invention, a relay or switching device is provided with a base plate of conducting material, such as sheet metal, of such size that it is adapted to form a closure for an opening in a grounded shield wall extending between the controlled audio frequency circuits and alternating current operating windings for the switching means, thereby permitting a plurality of such devices to be utilized in groups in or on a metal panel of a control apparatus.

In order that the invention may further be understood, attention is now directed to the accompanying drawing and the following description, together with the appended claims.

In the drawing, Figure 1 is a front view of a relay or switching means in a system embodying the invention,

Figure 2 is a side view thereof, both views being substantially full size, and

Figure 3 is a schematic circuit diagram of a relay or switching system embodying the invention and provided with a plurality of relays or switching means as shown in Figures 1 and 2.

Referring to Figures 1 and 2, 5 is a grounded panel of an apparatus involving a plurality of low level audio frequency circuits for which suitable circuit transfer or switching means is provided. The switching means comprises a metal base plate 6 adapted to fit over a panel opening 7 with a relay-operating coil 8, core 9, and armature 10 on one side thereof, and with movable and fixed insulated contact means on the opposite side thereof.

In the present example, the fixed contact means comprises two upper contact blades 11, 12 and two lower contact blades 13 and 14, each hav-

ing terminal members 15 secured to an insulating plate 16 mounted on the base 6.

The contact means further includes two pairs of opposed laminated spring contact fingers 20 and 21 forming extensions of two insulating arms 22 and 23 secured to a metallic spacer block 24 pivoted to rotate about a pivot pin 25 which extends through the block 24 and two supporting brackets 26, also mounted on the insulating plate 16.

The pairs of contact fingers are connected to terminals 28 which, in turn, are connected through flexible leads 29 with base terminal members 30. As will be seen, the contact arrangement of the present example provides a double-pole, double-throw switch means, although any other suitable contact or switching arrangement may be provided wherein one or more pairs of laminated contact fingers 20-21, are pivotally mounted, and insulated to move directly from one contact to another with a sliding or wiping action, the contact engaged being in the plane of movement of the contact fingers and being blade-like and gripped on each side by the contact fingers.

The operation of the contacts is provided through a mechanical link or rod 35 which extends through a small opening 36 in the shield plate or base 6, between a pivot pin 37 in the switch lever base 24 on the opposite side of the pivot 25 from the contacts 20-21, and a pivotal connection 38 at one end of the armature 10. A coil spring or other suitable tension means 39 surrounds the link 35 and presses against the end of the armature 10 and the end of the block 24 to take up any play in the bearings about the pivot axes 25, 37 and 38.

The armature is positioned with one end adjacent the pole piece 40 of that portion of the core 9 which extends through the coil 8, while, at an intermediate point between the pivot connection 38 and the portion opposite the pole piece, the armature is pivotally mounted as indicated at 41 between a pair of frame members indicated at 42, which serve to clamp and hold the core. A retracting spring 43 is connected between the armature and a fixed connection 44 on the frame 42 to withdraw the armature from the pole piece 40 and against the inner end of a stop screw 45 which extends through the base plate 6 and the insulating base 16.

By adjusting the screw 45, the armature 10 may be positioned, with the winding deenergized, to move the switch lever and the contacts 20-21 into proper alignment with the contacts 11-12 as shown in Fig. 2. When the coil 8 is energized the armature is attracted, causing movement of the lower end and the pivot connection 38 to the left, thereby transmitting a corresponding movement to the pivot connection 37 on the switch lever means and causing the contacts 20-21 to move to the right into engagement with the contacts 13-14.

The same coil terminals and connections may be provided in any suitable manner, one terminal being indicated in Figure 2, at 48, to which a lead wire 49 is connected. The lead wire 49 extends from the coil 8 along a casing wall 50 for the apparatus which is in spaced relation to the panel or wall 5, forming a compartment within which is located the operating magnet or motor means 8 and the alternating current supply circuit connections therefor. On the opposite face of the wall or panel 5 where is provided the signal carrying and controlling contacts of the switch means and the connection leads there-

for indicated at 52, these leads being broken in Figure 2 in order to show the construction of the relay device more clearly.

With this arrangement, it will be seen that the 5 operating or free ends of the armature and switch means provide a relatively wide range of travel, while the link-connected opposite ends move through a relatively short distance. The armature and switch arms are arranged for substantially parallel operation on opposite sides of the shield wall 5. This arrangement has the further 10 advantage that it overcomes the disadvantages encountered in previous designs and enumerated hereinbefore. The operation of the contacts is 15 accomplished wholly by means of a mechanical link through a small opening in the shield plate or wall at a point substantially remote from the contact end of the switch means.

This arrangement permits the coil or operating 20 windings 8 to be energized from any suitable alternating current source, while being entirely shielded from the low level audio frequency control contacts, as the metal base plate 6 forms, when mounted, an integral part of the 25 shielding main panel 5 of the apparatus. Therefore, it will be seen that the wiring to the relay coil or coils, where a plurality are mounted upon a single panel in a group, may be located on one side of the panel, while low level audio frequency 30 wiring for the contacts may be located on the opposite side of the panel.

Furthermore, this arrangement in the switching means provides for eliminating the difficulty hereinbefore experienced in keeping low voltage 35 contacts sufficiently clean to function properly. Because of the pressure exerted on each side of the stationary contact by the pairs of contact arms 20 and 21, a continuous sliding or wiping contact is provided, which serves to remove dirt 40 or corrosion ahead of the moving arm, instead of compressing and holding it as in conventional types of relays.

Accordingly, the contacts wipe clean as they 45 operate and do not introduce into the circuit any appreciable contact resistance which, in higher voltage relays, is normally broken down by the applied voltage. In low level audio frequency 50 circuits, as hereinbefore mentioned, there is no appreciable transfer of current or voltage through the circuit or circuits connected with the relay.

Additionally, the construction shown and described overcomes the contact vibration hereinbefore considered, for the reason that relatively 55 long contact arms are normally free to vibrate at the contact end, whereas, in the present arrangement, the movable arm is damped and held in place by the gripping action of the contacts on each side of the fixed contact. The friction 60 at the free end of the movable contact means, plus the restoring spring pressure, is sufficient to keep the relay contacts from changing position during a heavy shock or in the presence of vibration. It is, therefore, highly desirable for use in connection with gun-fire control circuits and the like.

Referring now to Figure 3, along with Figures 1 and 2, the panel 5 of the apparatus is indicated schematically with the contacts of several relay or switch devices schematically indicated at 60, 61, 62 and 63 for four relay devices, the operating 70 coils of which are indicated on the opposite side of the panel 5 at 64, 65, 66 and 67. Each coil is provided with an operating armature 68 connected as indicated with the contacts for

which the operating coils are provided. To minimize electrical disturbances in the control circuits, each relay coil may be provided with a shunt capacitor 69.

Each relay device serves to connect a low level signal input circuit, such as microphone circuits 70, with an audio frequency output circuit 71, which is connected through a preamplifier system 72 and a power amplifier 73 to an output bus circuit 74 to which suitable output devices, such as loudspeakers 75, may be connected as indicated.

The microphones 76 connected with the leads 70 are provided each with a control button or suitable switching means 77, 78, 79 and 80, for controlling the relays and the connection of the respective microphone to the output line 71. In the present example, the relay coils 64-67 are energized from alternating current supply leads 81 and control leads 82 connected with the control buttons 78-80 as shown, whereby control buttons 78-80 serve to operate the coils or relays 64-67, respectively.

It will be noted that the microphones may be extended to suitable remote points, while the control is centered at one point in such a manner that the audio and operating circuits are isolated by the shield wall 5. It is also desirable that the leads 70 and 71 be shielded as indicated by the shield connections 82.

In a system as shown in Figure 3, it has been found that switching operation of relatively low level audio frequency circuits in connection with high gain amplifier devices, as at 72 and 73, is highly satisfactory, being substantially without hum pickup as ordinarily experienced with control circuits of this type when groups of relay magnets are operated with alternating current.

The contacts are preferably silver plated on the operating surfaces and have been found to have an operating life of several hundred thousand operations. A thin lubricant of petrolatum and zinc dust for the contact has been found to extend the operating life considerably without affecting the electrical operation or contact resistance.

I claim as my invention:

1. The combination with a control panel having a switch opening, of a shield plate adapted to provide a closure for said opening, a pivotally mounted switch member on one side of said plate comprising a pair of opposed spring contact fingers and a fixed contact blade engaged on opposite sides by said fingers, means for moving said fingers out of and into gripping engagement with said blade comprising a pivotally mounted armature on the opposite side of said shield plate, means providing a single opening in said plate, a link member extending through said opening and connecting said armature and switch member, electromagnet means for actuating said armature, and spring means for retracting said armature with respect to said electromagnet means.

2. A relay operated low level audio frequency switching device having an operating winding, a magnetic core and an armature associated with said winding, a switch comprising pivotally mounted spring contact fingers and a fixed contact blade engaged by said fingers, means providing a metallic shield wall interposed between said switch and said operating winding, and a link connection extending through said shield wall between said switch and armature for mov-

ing said switch in response to energization of said winding.

3. A low level audio frequency relay switch comprising in combination, a grounded shield wall having a removable portion providing a base plate, a pair of opposed spring contact members, pivotal mounting means for said members on one side of said plate providing movement of said members in pairs, a fixed switch contact blade engaged on opposite sides by said contact members, means for moving said contact elements into and out of engagement comprising a pivotally mounted armature on the opposite side of said base plate and a link member extending through said base plate and connecting said armature and pivotal mounting means, and an alternating current winding for actuating said armature.

4. A low level audio frequency relay switch comprising in combination, a shield plate adapted to provide an apparatus shield cover, a pivotally mounted switch member having an arm carried thereby, a pair of opposed spring switch contact members forming an extension of said arm, a fixed switch contact blade gripped on opposite sides by said contact members, alternating current motor means for moving said contact members out of and into engagement therewith comprising a pivotally mounted armature on the opposite side of said shield plate, and a link member extending through said shield plate and connecting said armature and pivotally mounted switch member.

5. A low level audio frequency relay switch comprising, in combination, a grounded shield wall having a removable portion providing a base plate, a pair of opposed spring contact members, pivotal mounting means for said members on one side of said plate providing movement of said members in pairs, a fixed switch contact blade engaged on opposite sides by said contact members, means for moving said contact elements into and out of engagement comprising a pivotally mounted armature on the opposite side of said base plate and a link member extending through said base plate and connecting said armature and pivotal mounting means, an alternating current winding for actuating said armature, and low level audio frequency terminals connected with said contact members on the opposite side of said base plate.

6. A remote control system for low level audio frequency signal conveying circuits comprising, in combination, a plurality of low level audio frequency signal conveying circuits, alternating current control circuits for said system, a metallic shield wall interposed between said signal conveying and control circuits, a pair of opposed pivotally mounted spring switch members connected with certain of said signal conveying circuits on one side of said wall, a fixed switch contact blade engaged on opposite sides by said members, means providing a connection with said contact members for one of said signal conveying circuits, alternating current motor means for moving said contact elements out of and into engagement comprising a pivotally mounted armature on the opposite side of said base plate and shield wall, and a link member extending through said base plate and connecting said armature and pivotal mounting means for said contact members, said motor means including a winding connected with one of said control circuits.

7. A remote control system for low level audio frequency signal conveying circuits comprising,

in combination, a plurality of low level audio frequency signal conveying circuits, alternating current control circuits for said system, a metallic shield wall interposed between said signal conveying and control circuits having a removable portion providing a base plate, spring contact members connected with certain of said signal conveying circuits on one side of said wall, pivotal mounting means for said members carried by said base plate, a fixed switch contact blade engaged by said contact members, means providing a connection with said contact blade for another of said signal conveying circuits, alternating current motor means for moving said contact mem-

bers out of and into engagement with said blade comprising a pivotally mounted armature on the opposite side of said base plate and shield wall, a link member extending through said base plate and connecting said armature and pivotal mounting means for said contact members, said motor means including an alternating current actuating winding connected with one of said control circuits, a low level signal pickup device connected to one of said signal conveying circuits, and means for applying an alternating current to said winding through one of said control circuits.

WILLIAM J. MORLOCK.
